COMBINED TABLETOP, AQUARIUM AND COVER
THEREFOR OR SIMILAR ARTICLE

Robert Erik Miller, 11 Hidden Valley Road,
Monrovia, Calif. 91016

Filed Jan. 17, 1972, Ser. No. 218,655

Term of patent 14 years

Int. Cl. D30—02

U.S. Cl. D30—8

FIG. 2

FIG. 1 is a top and side perspective view of a combined tabletop, aquarium and cover therefor, showing my new design; and

FIG. 2 is a fragmentary top and side perspective view thereof with the cover removed and omitted.

I claim:

The ornamental design for a combined tabletop, aquarium and cover therefor or similar article, substantially as shown and described.
